SHUTTLE CONSTRUCTION

Filed Dec. 15, 1926

13 INVENTOR:
WASHINGTON L. HALL,
BY
Wiederholt, Van Buren & Co.
ATTORNEYS.

UNITED STATES PATENT OFFICE.

WASHINGTON L. HALL, OF PHILADELPHIA, PENNSYLVANIA, ASSIGNOR TO JAMES H. BILLINGTON COMPANY, OF PHILADELPHIA, PENNSYLVANIA, A CORPORATION OF PENNSYLVANIA.

SHUTTLE CONSTRUCTION.

Application filed December 15, 1926. Serial No. 154,867.

This invention, stated in general terms, has reference to a shuttle construction and specifically relates to a new and useful yarn or thread tensioning device for loom shuttles and it further relates to a thread or yarn tensioning device which may be threaded easily and which will maintain a uniform tension upon the thread and which will moreover prevent an entangling of the thread or 10 yarn.

One object of the present invention is to combine with a structure as just above stated, a metallic member having a vertical reinforcement against which the weakened 15 wooden wall of the shuttle may abut and be clamped thereto, so that in shuttle movement shock and attrition may be reduced to a minimum.

A further object of the present invention resides in the provision of general details of 20 construction and in the arrangement and combination of parts for attaining the results sought by the said leading object.

A further object resides in the provision 25 of a tensioning device, adapted to be inserted and embedded in the throat end or discharge end of a shuttle, as a body member and a hinged tension member, the latter being pressed against the body with a uniform tension, as for example by a helical compression 30 spring.

With these and other objects in view, the invention consists of the novel construction hereinafter described and finally claimed.

The nature, characteristic features and scope of the invention will be more fully understood from the following description taken in connection with the accompanying drawings forming part hereof, and in which:

Figure 1, represents a top or plan view, shown partly in section, on line 1—1 of Fig. 2, illustrating a shuttle having mounted therein a device embodying the invention.

Figure 2, represents a side elevation of the 45 same.

Figure 3, represents a section on line 3—3 of Fig. 2.

Figure 4, represents a bottom plan view 50 of the device embodying the novel construction.

Figure 5, represents a side elevation of the same.

Figure 6, represents a side elevation of the

hinged friction or tensioning member shown 55 detached.

Fig. 7, is a view in detail hereinafter referred to.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged 60 and organized and that my invention is not limited to the precise arrangement and organization of the instrumentalities as herein shown and described.

In the accompanying drawings, in which 70 like reference characters indicate like parts, the shuttle body 1 is of the usual construction and having therein the longitudinal bobbin chamber 2 terminating in the shuttle throat 3. The tensioning device 4 of my 75 novel invention, shown particularly in Figs. 4 and 5, is seated or housed within a vertical cylindrical chamber 5, in the solid end portion 6 of the shuttle, slightly in advance of the bobbin chamber 2, as will be seen from 80 Figs. 1 and 2.

The tensioning device 4 of my novel construction comprises a substantially cylindrical or disk-like base part 7, having a substantially plane lower surface 8, provided 85 with a hinged tension or friction member 10. This part 7 is provided with the two opposed hinged sockets or recesses 11 and 12, for the reception of the respective hinged pins or 90 pivot trunnions 13 and 14 of the hinged friction member 10. The hinged friction member 10, is provided with a transversely extending, friction nose 15, which is adapted to bear against the yarn or thread.

The tensioning device 4 also includes an 95 upper truncated cylindrical friction member 16, formed integrally with the base 7 and having a transversely extending, lower and inclined friction surface 17, against which the movable friction jaw or nose 15 of the 100 movable tension friction member 10 is adapted to bear, and to have come therebetween the thread or yarn. The peripheral contour of both the upper member 16 and the lower base portion 7 which are of metal are generally cylindrical so as to fit snugly within 105

the cylindrical chamber 5 of the wood shuttle in a manner shown particularly in Figs. 1 and 3.

A helical compression spring 18 housed 5 within a suitable chamber or bore 19, is interposed between the movable friction member 10 and the removable threaded plug 20, screw-threaded into the solid bottom of the shuttle. A lower, pendant, guiding projection 10 21, may be provided upon the underside of the movable or hinged friction member 10, in order to guide and retain in position the upper end of the helical compression spring 18. By thus inserting the helical 15 compression spring 18, into the bore or chamber 19 and securing the outer end thereof, by the detachable screwthreaded, plug 20, the movable or hinged friction member 10 is urged upwardly against the inclined transverse friction surface 17 at the stationary 20 portion of said tensioning device.

In order to secure the tensioning device in position within the chamber 5, a vertical screw 22, or other fastening device, may be 25 employed extending through a suitable opening, 23, in the basal portion of the tensioning device 7 and threaded into the body of the shuttle as shown in Fig. 3. A further fastening device 24, may also be employed in the 30 form of a machine screw, extending through the weakened wood wall of the shuttle, from without and threaded into the upper portion 16 of the metal tensioning device, which latter is extended well up toward the top surface 35 of the shuttle.

In order to permit the threading of the shuttle, a vertically disposed slot 25 arranged upon an arc of a circle is provided in the fore-part of the shuttle, starting from the center 40 of the chamber 5 and terminating at the fore-part of the shuttle on the side and extending down to the horizontal slot 26, see Fig. 2, which slots materially weaken the shuttle wall. The slot 26 in turn extends to and terminates in a horizontal, transverse eye bore 27, which extends inward from the outer side 45 of the shuttle to the vertical chamber 5. Thus, thread 28, after passing through the shuttle throat, is drawn down into the vertical slot 25 and into the horizontal slot 26 until it is finally drawn into the eye bore 27. A horizontal slot 29, see Fig. 5, is provided in the stationary or body portion of the tensioning device, intermediate of the cylindrical base 7 and the upper portion 16 and substantially in alignment with the horizontal slot 26 in the body of the shuttle, said slot 26 55 extending to approximately the middle of said tensioning device. Thus, thread 28 after being first drawn into the horizontal slot 26 in the body of the shuttle is then drawn into the horizontal slot 29 in the tensioning device and thus finally drawn into the inclined friction surface 17, and the movable friction nose 60 65 15 of the tensioning device.

In order to reduce the friction upon the thread as it leaves the eye bore or aperture of the shuttle, a pair of opposed metallic, anti-friction members 30 and 31, are provided at the discharge end of said bore. Each of said members 30 and 31 comprises a smooth, cylindrical, metallic rod or pin embedded in the body of the shuttle and positioned tangent to the bore 27 directly in advance of and behind said bore respectively. Thus, as the shuttle moves in either direction, the yarn 28 will be drawn against one of these antifriction pin or eye members 30 and 31. While the pin 31 extends well below the eye bore 27, the pin 30 is bevelled at its lower end and terminates at a place substantially in alignment with the lower edge of the horizontal bridge 32. By this means the thread may be drawn through the slot 26 upon the lower end of the pin 30. In order to prevent the unthreading of the shuttle by the entrance of the thread into the slot 26, a wire or other metallic bridge is provided extending transversely across the eye bore of the shuttle and slightly exterior with respect to or in front of the pins 30 and 31. The bridge 32 may be secured by two terminal prongs 33, embedded in the body of the shuttle. The upper edge of the bridge 32 is slightly above the lower terminal of the pin 30 so as to retain the thread passing through the eye of the shuttle at a level slightly above the lower terminal of said pin 30 and thereby prevents the unthreading of the same.

The device as above described, particularly the parts 16 and 24, serve to provide a relatively rigid and fixed connection between the weakened and non-weakened parts of the shuttle fore-end as provided by the slotted portions 25-26. Thus, in the reciprocal movement of the shuttle, shock and attrition, as would ordinarily result in splitting or splintering of the weakened shuttle part is reduced to a minimum by reason of said parts 16-24, in which connection it is to be noted that the part 16 extends well up toward the top of aperture 5. Fig. 7 is similar in all respects to Fig. 5 except that the position of the part 15 is in tilted or tension position in contradistinction to horizontal position as shown in Fig. 5.

What I claim is:

1. In a shuttle construction, in combination, a weakened shuttle throat having a vertical, cylindrical chamber, a tensioning device fitted to said chamber, said device having means including a vertical, rigid extension for abutting against the weakened wall of said shuttle, and means as a screw for securing said extension to said weakened wall.
2. In a shuttle construction, in combination, a weakened shuttle throat having a vertical, cylindrical chamber, a tensioning device fitted to said chamber, said device having means including a vertical, rigid extension for abutting against the weakened wall

of said shuttle, means as a screw for securing said extension to said weakened wall, and a pivotal tensioning device operatively connected with said extension.

- 5 3. In a shuttle construction, in combination, a weakened shuttle throat having a vertical, cylindrical chamber, a tensioning device fitted to said chamber said device having means including a vertical, rigid extension
10 for abutting against the weakened wall of

said shuttle, means including a bolt for securing said extension to said weakened wall, a pivotal tensioning device operatively connected with said extension, and means for adjusting the pivotal tensioning relation of said 15 device.

In testimony whereof, I have hereunto signed my name.

WASHINGTON L. HALL.
